WITNESS:

UNITED STATES PATENT OFFICE.

JOSEPH ZOPFI, OF ELMIRA, NEW YORK.

DESIGN FOR A GAME APPARATUS.

59,531.

Specification for Design.

Patented Oct. 25, 1921.

Application filed September 18, 1920. Serial No. 411,332. Term of patent 7 years.

To all whom it may concern:

Be it known that I, JOSEPH ZOPFI, a citizen of the United States, residing at Elmira, in the county of Chemung and State of New York, have invented a new, original, and ornamental Game Apparatus, of which the following is a specification, reference being had to the accompanying drawing, forming a part thereof.

Figure 1 is a front elevation; and
Fig. 2 is a side elevation.

I claim:
The ornamental design for a game apparatus, as shown.

JOSEPH ZOPFI.
